(57) **CLAIM**

The ornamental design for a lamp, as shown and described.

DESCRIPTION

Fig. 2.1 illustrates a bottom perspective view of a lamp, showing our new and ornamental design;

Fig. 2.2 illustrates a top plan view thereof;

Fig. 2.3 illustrates a partial bottom plan view thereof;

Fig. 2.4 illustrates a front elevation view thereof;

Fig. 2.5 illustrates a partial side elevation view of thereof;

and

Fig. 2.6 illustrates a partial side elevation view of thereof. The broken lines in the drawings illustrates portions of the lamp which forms no part of the claimed design.

1 Claim, 4 Drawing Sheets
